United States Patent Office

Des. 217,462
Patented May 5, 1970

217,462

TELEPHONE WALL PANEL

**Louis Philippe Fortin, Montreal, Quebec, Canada, assignor
to Namofil Inc., Montreal, Quebec, Canada**

Filed Jan. 17, 1969, Ser. No. 15,399

Term of patent 14 years

Int. Cl. D14—03

U.S. CL. D26—14

The figure is a front elevation of a telephone wall panel showing my new design.

I claim:

The ornamental design for a telephone wall panel, as shown and described.
